BUMPER GUARD

Sidney Yakerson, New York, N.Y., assignor to Metal-crafters Specialties, Inc., a corporation of New York

Filed Oct. 9, 1968, Ser. No. 13,903

Term of patent 14 years

Int. Cl. D12—14

U.S. Cl. D14—6

FIGURE 1 is a perspective view of a bumper guard showing my new design;

FIGURE 2 is a side elevational view thereof;

FIGURE 3 is a front elevational view thereof;

FIGURE 4 is a bottom view thereof;

FIGURE 5 is a top view thereof; and

FIGURE 6 is a side elevational view of a modified form thereof; and

FIGURE 7 is a side elevational view of a further modified form thereof.

It is to be understood that the front, top and bottom views of the forms shown in FIGURES 6 and 7 are the same as the form shown in FIGURES 1 through 5.

I claim:

The ornamental design for a bumper guard, as shown and described.
